UNITED STATES PATENT OFFICE

91,016

DESIGN FOR A BLOCK TABLE OR SIMILAR ARTICLE

Herman E. De Vries, New York, N. Y., assignor to H. T. Cushman Mfg. Co., North Bennington, Vt.

Application April 13, 1933. Serial No. 47,772

Term of patent 3½ years

To all whom it may concern:

Be it known that I, HERMAN E. DE VRIES, a citizen of the United States, residing at New York city, in the county and State of New York, have invented a new, original, and ornamental Design for a Block Table or Similar Article, of which the following is a specification, reference being had to the accompany drawing, forming a part thereof.

The figure is a perspective view of a block table showing my design.

I claim:

The ornamental design for a block table or similar article, as shown.

HERMAN E. DE VRIES.
